LUMINESCENT TUBE

Frederick E. Balcar, Elizabeth, N. J., assignor
to Air Reduction Company, Inc., New York,
N. Y., a corporation of New York

No Drawing. Application March 29, 1930
Serial No. 440,165

5 Claims. (Cl. 176—122)

This invention relates to gas-containing tubes which emit light when energized by an electric current.

Such tubes are well known, particularly those containing neon, which emit a reddish orange light of great brilliance. Tubes containing various mixtures of gases and vapors have also been used to produce colors such as blue and green.

It is the object of the present invention to provide tubes with mixtures of gases and/or vapors which are caused by the passage of current to emit light of various colors and shades of distinctive quality.

In carrying out the invention I may employ tubes of the usual form made of glass, quartz or any suitable transparent or translucent material. Such tubes are generally provided with electrodes disposed therein with suitable lead-in wires extending through the walls. The electrodes may be disposed outside the tubes, however, with suitable conductors connected to a source of current.

I have discovered that the quality and characteristics of the light emitted by a neon tube may be modified to a very marked extent by the addition thereto of relatively small amounts of other rare gases such as krypton and xenon. Thus I find that by adding from 5% to 25% of either krypton or xenon mixtures thereof to the neon in the tube, the characteristic color of the neon light disappears. The color of the light emitted varies with the nature and proportions of the gases used.

The color of the light emitted by such tubes may be modified further by the use of colored gas tubes. Thus if amber or yellow glass is used, the light emitted is changed to yellowish green.

If a drop of mercury is introduced to the tube containing such gas mixtures, the mercury is vaporized by the heat resulting from the passage of current through the tube and the vapor mingles with the gases in the tube. When such a tube is energized, the light emitted is a brilliant blue if the tube is made of substantially colorless glass. The color is changed to green when the tube is made of amber or yellow glass.

As an example of the invention, I prefer to employ a mixture of about 90% neon and 10% of krypton and/or xenon or mixtures of the latter gases. The gases may be introduced to and sealed in a tube of the usual construction with suitable electrodes at a pressure of, for example, 7 to 10 mm. of mercury. Such a tube may be energized by a current of from 25 to 30 milliamperes and will glow with a pale rose color. If

the tube is made of amber or yellow glass, the color of the light emitted is yellowish green.

In a tube containing a gaseous mixture of similar composition, I may introduce a drop of mercury. As soon as the mercury is vaporized by the heat afforded by the passage of current therethrough, the color of the light emitted will be blue, provided that the tube is made of colorless glass. If a tube of amber or yellow glass is used, the light emitted is a brilliant green.

One of the advantages of using krypton and xenon mixed with neon is that such a mixture produces almost a perfectly even distribution of radiation throughout the visible spectrum. Neon, for instance, is deficient in blues and greens. The spectrum of krypton is rich in yellow, green and blue. The combination of neon with krypton, in which certain lines of krypton are relatively intense, produces an even distribution of radiation, so that the gas may be used advantageously with glasses of all colors, particularly yellow, green and blue. Its ability to give a blue color is particularly useful, as a deep blue may be obtained without the use of mercury, which is troublesome and has a tendency to produce dark spots on the walls of the tube, especially in a tube which has been run for a considerable number of hours.

Another advantage in the use of krypton and xenon mixed with neon is that because of their widely different molecular weights and other atomic properties, changes in current density in the discharge tube affect the color of light emitted to a marked extent. For instance, in a glass tube having both large and small diameters and containing krypton and neon, the light emitted at the large diameter will be pale rose, and at the small diameter it will be pink. Neon and xenon may be used to produce a green light in the section of large diameter, and almost a white light in the section of small diameter tubing. Because of this variation of color produced by change of current density, color of a given tube may be changed by changing the current through the tube, and a very attractive tube is one in which the current is varied continuously.

It is possible, in accordance with the invention, to produce lights of various colors by proper selection and combination of the gases and vapors employed and of the color of the tubes which contain the gas mixtures. The invention affords numerous advantages and particularly the possibility of combining lights of different colors for display purposes.

Various changes may be made in the details

of construction and arrangement of the tubes and the compositions of the mixtures employed therein, without departing from the invention or sacrificing any of the advantages thereof.

5 I claim:

1. A luminescent tube containing neon and a gas of the group consisting of krypton and xenon, the gas from said group being present in an amount sufficient to alter the color of the emitted

10 light.

2. A luminescent tube containing a gaseous mixture of neon with from 5% to 25% of a gas of the group consisting of krypton and xenon, the gas from said group being present in an amount

15 sufficient to alter the color of the emitted light.

3. A luminescent tube containing approximately

90% of neon and approximately 10% of a gas of the group consisting of krypton and xenon, the gas from said group being present in an amount sufficient to alter the color of the emitted light.

4. A luminescent tube containing neon and a gas of the group consisting of krypton and xenon, the gas from said group being present in an amount sufficient to alter the color of the emitted light, together with mercury.

5. A luminescent tube of yellow glass containing neon and a gas of the group consisting of krypton and xenon, the gas from said group being present in an amount sufficient to alter the color of the emitted light.

FREDERICK R. BALCAR.
